US00D618324S

(12) **United States Design Patent**
Yu

(10) **Patent No.:** **US D618,324 S**
(45) **Date of Patent:** **** Jun. 22, 2010**

(54) **BEVELED PERIPHERAL INTERIOR EDGE
OF SINK BASIN BOTTOM**

(76) Inventor: **Shujen Yu**, 42 Colony Rd., Edgewater, NJ (US) 07020

(**) Term: **14 Years**

(21) Appl. No.: **29/336,103**

(22) Filed: **Apr. 28, 2009**

(51) **LOC (9) Cl.** 23-02

(52) **U.S. Cl.** D23/308

(58) **Field of Classification Search** D23/284-287, D23/290-293.1, 308; 4/619, 637, 639-640, 4/642

See application file for complete search history.

(57) **CLAIM**

The ornamental design for a beveled interior peripheral edge of sink basin bottom, as shown.

DESCRIPTION

FIG. 1 is a front perspective view of a sink from the top showing the ornamental design of the beveled peripheral interior edge of sink basin bottom. No claim is made to the sink portions depicted in broken lines as the entire sink is depicted for clarification.

FIG. 2 is a front perspective view of a sink from the top showing the ornamental design of the beveled peripheral interior edge of sink basin bottom as depicted in FIG. 1 without the broken lined portions of the sink.

FIG. 3 is a front perspective view of a sink from the bottom showing the ornamental design of the beveled sink basin bottom peripheral interior edge. No claim is made to the sink portions depicted in broken lines as the entire sink is depicted for clarification.

FIG. 4 is a front perspective view of a sink from the bottom showing the ornamental design of the beveled peripheral interior edge of sink basin bottom as depicted in FIG. 3 without the broken lined portions of the sink.

FIG. 5 is a perspective cross-section view thereof.

FIG. 6 is a top plan view thereof.

FIG. 7 is a bottom plan view thereof.

FIG. 8 is a front side elevational view thereof.

FIG. 9 is a right side elevational view thereof.

FIG. 10 is a rear elevational view thereof; and,

FIG. 11 is a left side elevational view thereof.
